(57) **CLAIM**

The ornamental design for a tilt and swivel hinge, as shown and described.

DESCRIPTION

FIG. 1 is a front isometric view taken from above the right front corner of a tilt and swivel hinge;

FIG. 2 is a rear isometric view taken from above the left rear corner of the tilt and swivel hinge of FIG. 1;

FIG. 3 is a front elevation view of the tilt and swivel hinge of FIG. 1;

FIG. 4 is a rear elevation view of the tilt and swivel hinge of FIG. 1;

FIG. 5 is a top plan view of the tilt and swivel hinge of FIG. 1;

FIG. 6 is a bottom plan view of the tilt and swivel hinge of FIG. 1; and,

FIG. 7 is an elevation view as viewed from the right side of the tilt and swivel hinge of FIG. 1, the left side being a mirror image of the right side.

The broken lines showing portions of the tilt and swivel hinge depict environment and form no part of the claim.
